Primary Examiner—Doris Clark

(74) Attorney, Agent, or Firm—Kenyon & Kenyon LLP

(57) **CLAIM**

The ornamental design for a bus shelter assembly, as shown and described.

DESCRIPTION

FIG. 1 is a front perspective view of an example embodiment of a bus shelter assembly showing my new design.

FIG. 2 is a front view thereof.

FIG. 3 is a right side view thereof.

FIG. 4 is a top view thereof.

FIG. 5 is a backside view thereof; and,

FIG. 6 is a left side view thereof.
